TOOL FOR MANIPULATING HEAD LAMP LENSES

Otto G. Hildebrand, Cleveland, Ohio

Continuation of application Serial No. 257,677,
February 21, 1939. This application November
30, 1939, Serial No. 306,823

5 Claims. (Cl. 294—64)

My invention contemplates, and has for its object to provide, a novel and effective tool of simple, inexpensive and sturdy construction, which is especially adapted for use in manipulating automotive vehicle head lamp lenses and other objects having smooth convexly curved surfaces to which the tool is to be applied.

The present application is a continuation of my application Serial No. 257,677, filed February 21, 1939.

More specifically my present invention provides a new and useful species of that tool genus which is characterized by (a) a flexible diaphragm adapted to engage a smooth surface to which the tool is applied, (b) a hollow casing of which the diaphragm constitutes one wall, and (c) force multiplying mechanism—e. g., a cam lever and linkage—for drawing the central portion of the diaphragm inwardly of the casing temporarily to give such diaphragm the conformation of a relatively deep cup and to establish a partial vacuum in a chamber defined by such cup and the smooth surface to which the tool is applied.

By reason of its novel features, hereinafter described and subsequently claimed, my new species of the aforesaid tool genus is applicable with equal facility and effectiveness to convexly curved surfaces (e. g., such as are presented by head lamp lenses) as well as plane surfaces (e. g., such as are presented by sheets of glass, flat walls, etc.). Earlier species of the same genus, so far as they have come to my attention, have been intended for, and, in actual practice have been applicable, with satisfactory facility and effectiveness, only to plane surfaces. Examples of such earlier species of the said genus are the plate glass handling implement of Burk Patent No. 2,127,154, and the brackets, for application to flat walls of various kinds, disclosed in Bau-meister Patent No. 276,336, Lang Patent No. 355,021, Lebherz Patent No. 1,840,400 and Shuler Patent No. 2,089,714.

The foregoing and other features, objects and advantages of my invention will appear from the following detailed description and accompanying drawings, in which

Fig. 1 is a view, partly in section and partly in elevation, illustrating my improved tool as it appears when brought into engagement with a head lamp lens to which such tool is to be adhered by atmospheric pressure acting against a partial vacuum developed by the subsequent manipulation of the tool;

Fig. 2 is an axial sectional view of the tool which may be regarded as taken on the line 2—2

of Fig. 3 and looking in the direction indicated by the arrows;

Fig. 3 is a plan view of the tool;

Fig. 4 is an axial sectional view of the tool as it appears, in relation to a head lamp lens, in the circumstances also depicted in Fig. 1—the section of such Fig. 4 being one which may be regarded as taken on the line 4—4 of Fig. 3 and looking in the direction indicated by the arrows;

Fig. 5 is a view similar to Fig. 4 but illustrating the tool as it appears when its operating lever has been actuated to draw the tool diaphragm into the conformation of a deep cup in which exists the partial vacuum against which atmospheric pressure acts to adhere the tool to the lens; and

Fig. 6 is an elevational view of a slightly modified embodiment of my invention.

Similar characters of reference refer to similar parts throughout the several views.

My improved tool comprises a metal frame member or casing 1 which is generally circular and provided with a small diameter portion 2 constituting a handle adapted readily to be grasped within a hand of the user. The outer surface of casing portion 2 may be roughened (e. g., as by knurling) to facilitate the hand grip thereon. (See Fig. 6.)

Casing 1 also comprises a larger diameter portion 3 which is coaxial with smaller diameter portion 2 and integrally connected therewith by an annular shoulder 2—a. Such shoulder 2—a constitutes an abutment against which the user may press, with that one of his hands which grasps the casing portion 2, while using the other hand to move the hereinafter described lever 4, when applying the tool to a head lamp lens or other suitable object. The lower edge of the casing portion 3 is curled to provide casing 1 with a rounded annular bead 3—a, constituting a pressure ring, which firmly may be pressed against the next-to-be-described rubber diaphragm 4 without cutting or preventing the necessary movements of the latter.

Carried with the casing 1 is a circular flexible rubber diaphragm 4 which has embedded therein a circular metal disc 5. Disc 5, being molded or otherwise suitably inserted in or attached to the rubber diaphragm 4, has its periphery evenly spaced from the periphery of the diaphragm, and is provided at its central portion with an inwardly extending lug 6 which conveniently is struck and turned from the metal of which disc 5 is formed. Pivoted at 7 to lug 6 is the inner end

of a link 8. Such link 8 is in the form of a metal strap which extends slidably but snugly through registering rectangular openings in casing 1, and a thrust washer 9 which bears against the smaller end of casing 1. Pivoted at 1-a to the outer end of link 8 is the lever 10 which, preferably, is so conformed from a single piece of metal as to have spaced apart end portions which straddle the outer end of the link. Such spaced apart end portions of the lever present a pair of similar spaced apart cam surfaces 11, eccentric to pivot 1-a, which bear directly against the thrust washer 9 (or directly against the casing 1 if the thrust washer be omitted). The web or back portion 10-a of the lever 10 has an end edge 10-b which is adapted to engage the link 8 when the lever is in the locking position depicted in Fig. 5.

The lever 10 serves as a very satisfactory mechanical means for flexing, stretching, and drawing the diaphragm 4 from the somewhat slightly flattened spherically concavo-convex conformation of Fig. 4 to the deeply cupped conformation of Fig. 5—and for locking the diaphragm in such deeply cupped conformation. The rubber diaphragm 4 is provided with an integral annular rib or bead 12 which extends around the inner surface of the diaphragm, at a uniform distance from the periphery of the diaphragm—such rib or bead acting to center casing 1 with respect to the diaphragm. Diaphragm 4 is not attached to casing 1 except through link 8. That surface of the peripheral portion 4-a of the diaphragm which lies against the casing bead 3-a is free to slide against and with respect to such casing bead 3-a when the diaphragm changes from its conformation of Fig. 4 to its conformation of Fig. 5, and vice versa. The peripheral portion 4-a of the diaphragm, extending as it does well outwardly beyond the periphery of the disc 5, is quite flexible, whereas the central portion of the diaphragm is substantially stiffened by disc 5. It also will be noted that the casing bead or pressure ring 3-a always engages the flexible peripheral portion 4-a of the diaphragm in a circular line spaced from the periphery of that face of the diaphragm against which such bead or pressure ring bears—although the distance between such periphery of such face and such circular line of engagement diminishes when the conformation of the diaphragm changes from that of Fig. 4 to that of Fig. 5.

It is of the utmost importance that the diaphragm be quite thick in relation to its diameter, that it be flexible at its periphery and relatively stiff at its central portion, that it be of larger diameter than and be unattached to the pressure ring, and that it carry means, preferably in the form of an integral bead, which lies within and loosely engages the pressure ring to maintain substantial concentricity between pressure ring and diaphragm when the parts are in the positions depicted in Figs. 1 to 4 both inclusive. As to the required thickness of the diaphragm, I will say that when the diaphragm has a diameter of approximately four inches when conformed as illustrated in Fig. 2, it should have a thickness of from three sixteenths of an inch to a quarter of an inch. In other words, the thickness of the diaphragm is preferably from three sixty-fourths (3/64) to one-sixteenth (1/16) of its diameter.

It is a peculiarity of the tool of the present invention, when in actual use, that the face of the diaphragm against which the bead or pressure

ring 3-a bears has its diameter noticeably diminished when the diaphragm is flexed, stretched and drawn from its conformation of Fig. 4 to its conformation of Fig. 5, but that the face of the diaphragm which lies against the surface to which the tool has attached itself does not noticeably suffer any change in its diameter during such change of the diaphragm from its conformation of Fig. 4 to its conformation of Fig. 5. In other words, the peripheral portion 4-a of the diaphragm appears not to slip, with respect to the smooth surface to which the tool is attaching itself, when the diaphragm changes from its conformation of Fig. 4 to its conformation of Fig. 5, but such peripheral portion of the diaphragm does noticeably slip with respect to the bead or pressure ring 3-a when the diaphragm is flexed, stretched and drawn from its conformation of Fig. 4 to its conformation of Fig. 5. But when the lever 10 is moved from its position of Fig. 4 to its position of Fig. 5 at a time when the diaphragm is not being pressed against any smooth surface, both faces of the diaphragm are very noticeably diminished in diameter.

In Fig. 1 the tool is shown as it appears when about to be secured to the lens of an automobile head lamp. Reference numeral 13 designates a head lamp casing which receives a reflector 14. Fitting over and in the reflector is a rubber gasket 15. The lens 16 has a convexly curved outer surface, as depicted in Figs. 1, 4 and 5, and also has a peripheral flange which lies between the gasket 15 and the margin of the lamp casing opening which is normally closed by the lens. The lens normally is held in appropriate assembly with lamp casing 13, reflector 14, and gasket 15 by a ring 17. The lower portion of the ring 17 is supported by a pin 18, and the upper portion of such ring is guided by a pin 19 and is urged outwardly by a spring 19-a. In order to assemble the lens 16, it is the practice first to force it rearwardly against the pressure of spring 19-a, then upwardly, and then forwardly at its lower portion and out of the casing 13. The head lamp thus briefly described is typical of many others comprising lenses to which the tool of my present invention may be applied.

In applying the tool to the convexly curved outer surface of lens 16 the portion 2 of the tool casing is grasped in one hand of the user and the tool is placed in the position depicted by full lines in Fig. 1. At such time the bead 12 maintains substantial concentricity between diaphragm 4 and the annular bead or pressure ring 3-a. Then the hand grasping the casing portion 2 exerts pressure against shoulder 2-a in the lines and in the direction of the feathered arrows 20, so that the annular bead, or pressure ring, 3-a of the casing will press against the flexible peripheral portion 4-a of the diaphragm, in a circular line spaced inwardly of the diaphragm periphery, snugly to clamp the diaphragm portion 4-a between the bead 3-a and the lens and firmly to press such portion 4-a of the diaphragm generally flatwise against the convexly curved surface of the lens, as illustrated in Fig. 4. Then with one hand of the user holding and pressing against the tool casing, as just described, the other hand of the user is employed to move the tool lever 10 from its full line position of Fig. 1 to its dotted line position of the same figure. Fig. 4 shows the lever 10 in its full line position of Fig. 1, whereas Fig. 5 shows such lever in the dotted line position of Fig. 1. The

lever 10 automatically locks in the position of Fig. 5.

When, with manual pressure being exerted against shoulder 2—a as above described, the lever 10 is moved from its position of Fig. 4 to its locked position of Fig. 5, the diaphragm 4 is flexed and stretched and drawn to its deeply cupped conformation of Fig. 5 without its flexible portion 4—a noticeably moving with respect to or losing air-tight contact with the convexly curved surface of the lens 16, even though the diameter of that face of the diaphragm, against which the bead or pressure ring 3—a bears, diminishes, and even though the peripheral portion 15 4—a of the diaphragm slips with respect to bead 3—a as the diaphragm assumes its deeply cupped conformation. Consequently, the partial vacuum developed in the chamber 21 (Fig. 5) between lens 16 and diaphragm 4 is such that 20 atmospheric pressure holds the tool tightly upon the lens as a convenient handle for use in manipulating the lens out of and into the head lamp casing.

Since the bed or pressure ring 3—a is of substantially less diameter than the diaphragm and always engages the flexible peripheral portion 4—a of the diaphragm in a circular line spaced from the diaphragm periphery, and since the face of the diaphragm bearing against the lens 30 16 (or other smooth surface to which the tool is being attached) experiences no diminishment of its diameter when the diaphragm is flexed, stretched and drawn to its deeply cupped position, it follows that at all times while the tool 35 is being attached to a lens, or other smooth surface, that face of the diaphragm which engages such surface is clamped against said surface in a circular line, which remains definitely and substantially spaced from, and need not shift with 40 respect to, the periphery of such diaphragm face. This is of the utmost importance in order to exclude air from the chamber 21 when the diaphragm is being flexed, stretched and drawn to its deeply cupped position in the course of the 45 application of the tool to a convexly curved surface such as is presented by a head lamp lens.

It is not at all necessary to moisten the outer surface of the lens 16 in order to attach the tool thereto as just described. The tool is quickly 50 released from the lens by moving lever 10 from its position of Fig. 5 to its position of Figs. 2 and 4—the diaphragm then acting to restore itself and other parts of the tool to their respective positions depicted in Fig. 2.

55 I am not the first to attempt the manipulation of head lamp lenses with temporary handles in the nature of tools comprising vacuum cups for effecting their attachment to the lenses (see the multiple vacuum cup tool of McKechnie Patent No. 2,091,050, and the tool comprising nested cups shown by Mattern Patent No. 2,127,181), but I do believe I am the first to provide for such purpose, or any purpose, a simple, inexpensive and sturdy tool, or any tool, affording the important functional advantages resultant from those novel features of tool construction and operation which are specified in the appended claims.

70 It has been found that the tool of the present invention has additional fields of usefulness in, for examples, handling flat sheets of glass, manipulating engine pistons into and out of their cylinders, and for removing small dents from flat and convexly curved surfaces of vehicle fenders 75 and other sheet metal structures.

Having thus illustrated and described a preferred embodiment of my invention, what I claim as new and desire to secure by United States Letters Patent, is:

1. In combination with a tool, for manipulating a lamp lens or other object having a convexly curved or plane surface to which the tool is applicable, comprising: a substantially circular flexible diaphragm, a frame member comprising a pressure ring, of substantially less diameter than said diaphragm, slidably disposed against one face of the diaphragm, said pressure ring lying wholly within and being spaced from the periphery of the diaphragm so that pressure transmitted to the diaphragm through said frame member and said pressure ring may be applied to one face of the diaphragm in a circular line substantially concentric with but spaced inwardly from the periphery of said diaphragm to press the peripheral portion of the other face of the 15 diaphragm flatwise against the surface to which the tool is applied, and diaphragm flexing mechanism, acting between the frame member and the central portion of the diaphragm, adapted when actuated to draw that face of the diaphragm which is contiguous to the pressure ring radially across and then through the pressure ring to give said diaphragm the conformation of a cup and to constrict the peripheral edge of that face of the diaphragm which is contiguous to the pressure ring into closer proximity to the aforesaid circular line of pressure application; a member 20 carried by the diaphragm, lying within and engaging but unattached to the frame member, tending to maintain concentricity between the 25 diaphragm and the pressure ring.

2. In combination with a tool, for manipulating a lamp lens or other object having a convexly curved or plane surface to which the tool is applicable, comprising: a substantially circular flexible diaphragm, a frame member comprising a pressure ring, of substantially less diameter than said diaphragm, slidably disposed against one face of the diaphragm, said pressure ring lying wholly within and being spaced from the periphery of the diaphragm so that pressure transmitted to the diaphragm through said frame member and said pressure ring may be applied to one face of the diaphragm in a circular line substantially concentric with but spaced inwardly from the 40 periphery of said diaphragm to press the peripheral portion of the other face of the diaphragm flatwise against the surface to which the tool is applied, and diaphragm flexing mechanism, acting between the frame member and the central 45 portion of the diaphragm, adapted when actuated to draw that face of the diaphragm which is contiguous to the pressure ring radially across and then through the pressure ring to give said diaphragm the conformation of a cup and to constrict the peripheral edge of that face of the diaphragm which is contiguous to the pressure ring into closer proximity to the aforesaid circular line of pressure application; an annular rib, carried by the diaphragm, lying within but 50 unattached to the pressure ring, said annular rib being disposed in close proximity to the pressure ring prior to flexing of the diaphragm to the conformation of a cup, and thus tending to maintain concentricity between the diaphragm and 55 the pressure ring.

3. In a tool for manipulating a lamp lens or other object having a convexly curved or plane surface to which the tool is applicable, a substantially circular flexible diaphragm, a frame mem- 75

ber in the form of a substantially bell shaped casing formed from sheet metal and provided at its open end with a curled edge constituting an annular pressure ring, said pressure ring being of substantially less diameter than said diaphragm and being slidably disposed against one face of the diaphragm, said pressure ring lying wholly within and being spaced from the periphery of the diaphragm so that pressure transmitted to the diaphragm through the casing may be applied to the diaphragm in a circular line substantially concentric with but spaced inwardly from the periphery of the diaphragm, a strap metal link pivotally attached to the central portion of said diaphragm and extending toward and through the closed end of the casing, and a lever cooperating with the end of said strap link which projects outwardly from the casing, and a cam surface on said lever which is adapted to bear against the adjacent portion of the casing to pull said strap link outwardly from the casing and thus draw that face of the diaphragm which is contiguous to the pressure ring radially across the pressure ring and into the casing, to give said diaphragm the conformation of a cup and to constrict the peripheral edge of that face of the diaphragm which is contiguous to the pressure ring into closer proximity to the pressure ring, said diaphragm being of such thickness in relation to its diameter, that the peripheral edge of its face engaging a surface to which the tool is being applied is not noticeably constricted when the diaphragm assumes the conformation of a cup.

35 4. In a tool for manipulating a lamp lens or other object having a convexly curved or plane surface to which the tool is applicable, a substantially circular flexible diaphragm, a frame member in the form of a substantially bell shaped casing formed from sheet metal and provided at its open end with a curled edge constituting an annular pressure ring, said pressure ring being of substantially less diameter than said diaphragm and being slidably disposed against one face of the diaphragm, said pressure ring lying wholly within and being spaced from the periphery of the diaphragm so that pressure transmitted to the diaphragm through the casing may be applied to the diaphragm in a circular line substantially concentric with but spaced inwardly from the periphery of the diaphragm, a strap metal link pivotally attached to the central portion of said diaphragm and extending toward and through the closed end of the casing, and a lever

cooperating with the end of said strap link which projects outwardly from the casing, and a cam surface on said lever which is adapted to bear against the adjacent portion of the casing to pull said strap link outwardly from the casing and thus draw that face of the diaphragm which is contiguous to the pressure ring radially across the pressure ring and into the casing, to give said diaphragm the conformation of a cup and to constrict the peripheral edge of that face of the diaphragm which is contiguous to the pressure ring into closer proximity to the pressure ring, said diaphragm being of such thickness in relation to its diameter, that the peripheral edge of its face engaging a surface to which the tool is being applied is not noticeably constricted when the diaphragm assumes the conformation of a cup, the smaller diameter portion of said bell shaped casing having its outer surface roughened to facilitate the manipulation of the tool.

5. In a tool for manipulating a lamp lens or other object having a convexly curved or plane surface to which the tool is applicable, a substantially circular flexible diaphragm, a frame member comprising a pressure ring, of substantially less diameter than said diaphragm, slidably disposed against one face of the diaphragm, said pressure ring lying wholly within and being spaced from the periphery of the diaphragm so that pressure transmitted to the diaphragm through said frame member and said pressure ring may be applied to one face of the diaphragm in a circular line substantially concentric with but spaced inwardly from the periphery of said diaphragm to press the peripheral portion of the other face of the diaphragm flatwise against the surface to which the tool is applied, and diaphragm flexing mechanism, acting between the frame member and the central portion of the diaphragm, adapted when actuated to draw that face of the diaphragm which is contiguous to the pressure ring radially across and then through the pressure ring to give said diaphragm the conformation of a cup and to constrict the peripheral edge of that face of the diaphragm which is contiguous to the pressure ring into closer proximity to the aforesaid circular line of pressure application, said diaphragm being of such thickness in relation to its diameter, that the peripheral edge of its face engaging a surface to which the tool is being applied is not noticeably constricted when the diaphragm assumes the conformation of a cup. 50

OTTO G. HILDEBRAND
